UNITED STATES PATENT OFFICE.

EARNEST A. SCOTT, OF AKRON, OHIO.

TRAFFIC-SIGNAL.

1,363,537.

Specification of Letters Patent. Patented Dec. 28, 1920.

Application filed April 26, 1919. Serial No. 292,358.

To all whom it may concern:

Be it known that I, EARNEST A. SCOTT, citizen of the United States, residing at Akron, in the county of Summit and State of Ohio, have invented certain new and useful Improvements in Traffic-Signals, of which the following is a specification.

This invention relates to an improved traffic signal for motor vehicles and has as its primary object to provide a construction whereby a driver may, with the use of signaling lamps employed, readily signal an intention to turn either to the right or left or to stop.

15 And the invention has as a further object to provide an approved signal lamp of such nature that the signal lights will be visible in the day time as well as at night and wherein reflection from the signal lamps will be reduced to a minimum so that the signal lamps will not reflect the rays from the headlights of a vehicle approaching in the rear to deceive the driver of the rear vehicle.

25 Other and incidental objects will appear hereinafter. In the drawings:

Figure 1 is a side elevation showing a conventional type of motor vehicle equipped with my improved signal,

30 Fig. 2 is a diagrammatic view showing the wiring system employed,

Fig. 3 is a vertical sectional view taken through one of the signal lamps, and

Fig. 4 is a sectional view taken at substantially right angles to Fig. 3.

In carrying the invention into effect I employ companion signal lamps which, for convenience, have been indicated as a whole in Fig. 2 of the drawings at 10 and 11 respectively. These signal lamps are mounted adjacent the rear end of the vehicle at opposite sides thereof, as suggested in Fig. 1, this view showing my improved signal in connection with a conventional type of motor vehicle 12. Since the signal lamps are identical in construction only one will be described.

Referring now more particularly to Figs. 5 and 6 of the drawings, it will be seen that each of the signal lamps includes a cylindrical casing comprising a body portion 13 to which is hinged an elongated cap 14 normally closing the casing body. At its front end the body 13 is contracted and is provided with a flared annular extension 15

which carries a red transparent pane 16. At its outer side the body is provided with a similar lateral extension 17 which carries a red transparent pane 18. Connected to the inner side of the body is a sleeve 19 adapted to receive a bracket or post therethrough for supporting the lamp in active position and provided with a suitable set screw for adjustably securing the lamp upon the post. Projecting radially inward from the wall of the cap 14, adjacent the inner end of said cap, is a plurality of spaced spring clips or brackets 20, and removably held by these brackets is a lens 21 which is preferably colored green. The brackets 20 are each preferably formed from a length of suitable resilient sheet metal connected at one end to the wall of the cap and having its intermediate portion rebent into substantial U-shape to engage the margin of the lens, the brackets removably sustaining the lens in place. Abutted against the brackets and closing the space between the periphery of the lens and the walls of the cap is a ring 22. This ring is formed from suitable sheet metal and is removably fitted in place. As will be seen, the ring will prevent the passage of light around the periphery of the lens. At its outer end, the cap is equipped with a flanged rim 23 against the flange of which is seated a closure pane 24 which is preferably of clear glass and is removably held in place by a resilient clamping ring 25. As will be observed, the rim, together with the pane 24 and the ring 25, may be removed as a whole from the outer end of the cap. Projecting within the body 13 of the casing at its lower side is a medial annular flange 26 which carries a set screw 27 and supported by this flange is a lamp socket 28 held by the set screw. The lamp socket may be of any approved type and removably receives an electric lamp 29.

The interior of the lamp casing, that is, the body 13 as well as the cap 14, is preferably coated black so that there will be no light reflection by the interior walls of the casing. Furthermore, particular attention is directed to the fact that owing to the length of the cap 14 and the mounting of the lens 21 adjacent the inner end of said cap, the cap will tend to shade or screen the lens so that, under ordinary circumstances, daylight rays will not directly strike the lens, 110

Consequently, when the lamp 29 is energized for illuminating the lens 21, the illuminated lens may be readily observed both in the day time and at night. Furthermore, it is 5 to be observed that since the lens 21 is screened by the outer end portion of the cap, rays from the headlights of a vehicle approaching in the rear of a vehicle equipped with my improved signal will not be reflected by the lens to deceive the driver of the approaching vehicle. Upon the energization of the lamp 29, a red light will show through the front pane 16, a similar light through the side pane 18, while a green 15 colored light will be seen at the rear end of the casing.

For controlling the lamps of the signals 10 and 11, I employ switches disposed in a preferably oblong casing 30 which is secured 20 upon the steering post 35 immediately adjacent the steering wheel 36.

The switches are controlled by levers 48 and 49 which project from the switch casing in opposite directions beneath the steering wheel 36 and are preferably of a length 25 to terminate at their outer ends beneath the rim of the wheel, so that the heads of the levers may, without removing the hands from the steering wheel, be readily grasped 30 by the fingers of the driver of the vehicle. Fixed to the outer side wall of the casing 30, adjacent opposite ends of said casing, are lamp sockets which receive pilot lamps 54 and 55.

35 In Fig. 2 I have diagrammatically shown the wiring system employed between the switches, the pilot lamps and the signal lamps. A wire 57 leads from one terminal of the switch controlled by the lever 48 to one terminal of the pilot light 54. A wire 58 leads from the other terminal of this light to one terminal of the signal 10. A wire 59 leads from the other terminal of the signal 10 to a storage battery or other 45 source of electrical energy 60 upon the vehicle. Leading from one terminal of the switch controlled by the lever 49 to one terminal of the pilot light 55, is a wire 61 and leading from the other terminal of said 50 pilot light to one terminal of the signal 11, is a wire 62. A wire 63 leads from the other terminal of the signal 11 and is connected with the battery 60. Bridging corresponding terminals of the switches is a bridge strip 64, and leading from the bridged 55 terminal of one switch to the battery is a wire 65.

Assuming now that the lever 48 is actuated to close the corresponding switch, current will then flow from the battery through the wire 59 and through the lamp of the signal 10 and thence through the wire 58 and through the pilot lamp 54, thence through the wire 57, through the switch, 60 the bridge strip 64 and wire 65 to the bat-

tery. The lamp of the signal 10 and the pilot lamp 54 will accordingly be simultaneously energized, the energization of the signal lamp indicating an intention on the part of the driver to turn to the right. The 70 pilot light will indicate to the driver that the signal is being displayed and will serve as a reminder to shut off the flow of current to the signal lamp after the turn has been made. Furthermore, should the lamp 75 of the signal burn out or, for any other reason, fail to properly operate, the pilot lamp would then also fail to operate so that the driver would be immediately apprised of the failure of the signal. Since the pilot 80 lamp 55 and the lamp of the signal 11 are electrically connected in a manner similar to the pilot lamp 54 and the lamp of the signal 10, the pilot lamp 55 will serve like functions in connection with the lamp of 85 the signal 11. Upon movement of the lever 49 to close the switch, current will then flow from the battery through the wire 65, the switch and through the wire 61 to the socket of the lamp 55, thence through this 90 socket and through the wire 62 to the lamp of the signal 11, and then return to the battery through the wire 63. The pilot lamp 55 and the lamp of the signal 11 will accordingly be simultaneously energized, the 95 signal indicating an intention of the driver to turn to the left. A signal to stop may be given by energizing both signal lamps. It will accordingly be seen that I provide a very effective type of signal which is adapted 100 for use in connection with substantially any conventional type of motor vehicle and which, when applied, may be readily operated from the driver's seat of the vehicle.

Having thus described the invention, what 105 is claimed as new is:

1. In a traffic signal, a signal lamp including a lamp casing comprising a body having light-transmitting openings at both ends, an elongated non-reflecting cap extending from the rear end of the body, means for supporting a lamp within the body, and a lens mounted adjacent the inner end of said cap to cover the rear end of the body. 110

2. In a traffic signal, a signal lamp including a lamp casing comprising a body having light-transmitting openings at both ends, an elongated non-reflecting cap normally closing the rear end of the body, means for supporting a lamp within the body, 120 brackets projecting inwardly from the wall of the cap adjacent the inner end of said cap, and a lens carried by said brackets to cover the rear end of the body.

3. In a traffic signal, a signal lamp including a lamp casing comprising a body having light-transmitting openings at both ends, an elongated non-reflecting cap normally closing the body, means for supporting a lamp within the body, brackets pro- 125

130

jecting inwardly from the wall of the cap adjacent the inner end of said cap, a lens carried by said brackets to cover the rear end of the lamp body, and a ring removably abutting the brackets and closing the space between the periphery of the lens and the wall of the cap.

4. A traffic signal comprising a substantially cylindrical lamp casing having a plurality of windows, one window being arranged to transmit light laterally and two windows being in alinement with each other and at an angle to the window transmitting

light laterally, an elongated non-reflecting cap normally closing the rear end of the 15 body, a lens mounted within the cap adjacent the inner end of the same to cover one of the alined windows in the casing, and a transparent pane closing the outer end of the cap, the cap preventing daylight playing upon the lens adjacent the inner end of the same and cutting off the lateral diffusion of light from the lens. 20

In testimony whereof I affix my signature.

EARNEST A. SCOTT. [L.S.]
